UNITED STATES PATENT OFFICE

JOHN A. SPENCER, OF NEWTON, MASSACHUSETTS, ASSIGNOR TO THE SPENCER THERMOSTAT COMPANY, OF CAMBRIDGE, MASSACHUSETTS, A CORPORATION OF MASSACHUSETTS

THERMOSTATIC SWITCH

Application filed June 17, 1930. Serial No. 461,802.

The present invention relates to gas burners especially of the type wherein the supply of fuel to the burner may be controlled by a valve operated by an electrical circuit.

5 Among the several objects of the invention may be noted the provision of a thermostatically controlled arrangement associated with a burner and electrically connected to a valve to stop the flow of fuel to the burner when 10 the burner is not lighted, although it is also evident that external heat may be employed in the operation of the device hereinafter described. Other objects will be in part obvious and in part pointed out hereinafter.

15 A convenient adaptation of the burner is to use the body of the burner as a means for controlling the closing and breaking of an electrical circuit to the valve, through the operation of a normally convexo-concave 20 spring metal diaphragm or disc, arranged to snap over dead center thereby transmitting motion to the member which closes and breaks the circuit through the valve. The body of the burner forms a temperature actuated 25 member for operating the disc to cause it to snap, the body of the burner and disc being an adaptation of the device described and claimed in my United States Patent 1,678,407, dated July 24, 1928, and the device herein described, represents a decided advance in the 30 art through its high degree of simplicity in its construction and its compact form.

The invention accordingly comprises the elements and combinations of elements, features 35 of construction, and arrangements of parts which will be exemplified in the structure hereinafter described, and the scope of the application of which will be indicated in the following claims.

40 In the accompanying drawing, in which is illustrated one of various possible embodiments of the invention,

Fig. 1 is an axial section of a burner and switch electrically connected with a motor 45 valve.

In the drawing, the body of a gas burner is made up of the tubular member 10 having a burner head 11 secured thereto, the head 11 having ports 12 therethrough for the passage 50 of gas to be burned. Secured to the head at

13 is the rod 14 of substantially greater length than the tube 10, the said rod extending through the tube. The tube 10 is made of metal having a relatively high coefficient of thermal expansion, such as brass or nickel 55 steel, the rod 14 having a lower coefficient of thermal expansion, such as "invar", the coefficient of thermal expansion of which is practically zero. Heat from the burner head is conducted to the tube 10, which expands, and 60 inasmuch as the rod 14 is connected to the tube 10 through the burner head 11, it will move with the expansion of the tube 10.

Although it is clear that the burner may be assembled in many ways, the drawing 65 shows a T-connection 15 secured to the end of the tube 10, the rod 14 passing through the joint and into a housing 16 containing the disc and contact members, the housing being secured to the connection 15. Gas 70 flows to the burner head from the line 17 and through the tube 10.

Within the housing 16 is secured the ring 18 provided with lugs 19, which lugs may form a continuous member bearing against 75 and supporting a diaphragm 20 which is adapted to snap over dead center to a reverse curvature. This snap action of the diaphragm 20 is effected by the motion of the rod 14 caused by expansion of the tube 80 10 because of heat conducted to it from the burner head 11 when the gas is lighted. Inasmuch as the movement of the rod is very slight it is desirable to provide means for the amplification thereof. This means 85 may consist of a plunger 21, with which the rod 14 engages, provided with lugs 22 which form a continuous member bearing against the diaphragm 20, the lugs 22 opposing the lugs 19, so that upon movement of the rod 90 14 against the plunger 21, there will be applied to the elastic diaphragm 20 oppositely directed forces at spaced intervals to apply flexing forces to the diaphragm so that the diaphragm will change shape abruptly in 95 response to temperature changes at the burner head.

Secured to the diaphragm and insulated therefrom by means of the bushing 29', is 100 a contact member 23 adapted to bridge the

contacts 24 and 25 when the diaphragm snaps to its normal position due to release of the flexing forces. When this bridging of the contacts occurs, current can flow through the circuit including the conductors 26 and 27. If desired, the housing may be grounded, as indicated at 28.

The disc 20 assumes its normal and "hot" position when the pressure of the rod 14 on the plunger 21 is substantially lessened and in this position (the opposite of that shown in the figure) it closes the contacts 24 and 25. However, pressure of the rod 14 on the plunger, caused by contraction of the tube 10, snaps the disc to its "cold" position (Fig. 1) thereby breaking the circuit.

As long as the burner is lighted, the circuit through the conductors 26 and 27 is closed by the seating of contact 23 across them thereby keeping a fluid supply valve 33 open. The fluid supply valve 33 comprises a known type of motor valve which is controlled by the circuit of the conductors 26 and 27. If the burner is extinguished, the tube 10 contracts through cooling and thus pushes the rod 14 down slightly and increases its pressure on the plunger 21, and causes the diaphragm 20 to snap back into its cold position, shown in the drawing, to break the contact; with the conductors 26 and 27 allowing the supply valve 33 to close to stop the flow of gas.

Inasmuch as the contact 23 is insulated from the diaphragm 20, no current will flow through the diaphragm, and arcing as the contact is made and broken is reduced to a minimum through the snap action of the diaphragm.

It is desirable to have lugs 19 of the ring 40 between the lugs 22 of the plunger 21 and the rod 14. This arrangement permits the pressure of the rod to be exerted upon the diaphragm near the periphery thereof, the peripheral edge being free, and thus adapted to change shape abruptly in response to flexing forces applied thereto, the burner serving as thermostatic means arranged to apply oppositely directed forces to the diaphragm at spaced points to flex the diaphragm abruptly in response to temperature changes.

It is to be understood that this invention is applicable to burners other than gas burners and also that the heat, producing the movement of rod 14 may be generated by means other than the burner itself.

In view of the above, it will be seen that the several objects of the invention are achieved and other advantageous results attained.

As many changes could be made in carrying out the above constructions without departing from the scope of the invention, it is intended that all matter contained in the above description or shown in the accom-

panying drawing shall be interpreted as illustrative and not in a limiting sense.

What is claimed is:

1. A burner comprising a tube, a distributing head at one end of said tube and a housing at the other end thereof, a rod in said tube, means in said housing operable to control a circuit, a valve operable to control the supply of fluid to said burner, said valve being controlled by said circuit and said means being actuated by the differences in the linear expansions of said rod and tube. 70

2. A burner comprising a tube, a distributing head at one end of said tube and a housing at the other end thereof, a rod in said tube, means in said housing operable to control a circuit, a valve operable to control the supply of fluid to said burner, said valve being controlled by said circuit and said means being actuated at critical temperatures by the different degrees of linear expansion of said rod and tube. 75

3. A burner comprising a tube, a distributing head at one end of said tube and a housing at the other end thereof, a rod in said tube, means in said housing operable to control a circuit, a valve operable to control the supply of fluid to said burner, said valve being controlled by said circuit and said means being actuated by the differences of the linear expansions of said rod and tube, said means comprising a snap-acting disc, mounted between oppositely disposed and unaligned concentric edges, one of said edges being movable under the pressure of said rod, whereby said disc may be flexed to either of its alternative positions by change of pressure of the rod on the edge. 90

4. A burner comprising a tube, a distributing head at one end of said tube and a housing at the other end thereof, a rod in said tube, means in said housing operable to control a circuit, and said means being actuated by the differences in the linear expansions of said rod and tube, said means comprising a snap-acting disc, oppositely disposed supports for the disc disposed at different radii with respect to the disc, said disc being mounted between said oppositely disposed supports, one of said supports being movable under the pressure of said rod, whereby said disc may be flexed to either of its alternative positions by change of pressure of the rod on the supports. 105

5. A burner comprising a tube, a distributing head at one end of said tube and a housing at the other end thereof, a rod in said tube, means in said housing operable to control a circuit, said means comprising a snap-acting diaphragm mounted between concentric abutments, the relative position between said abutments being adapted to be changed by the differences in the linear expansions of said rod and tube, whereby said diaphragm is flexed to its alternative positions. 120

6. A burner comprising a tube, a distributing head at one end of said tube and a housing at the other end thereof, a rod in said tube, means in said housing operable to control a circuit, said means comprising a snap-
5 ating disc, a switch operated by said disc, said disc being mounted near its outer edge between oppositely disposed concentric abutments, the relative position between said abutments being adapted to be changed by
10 the differences in the linear expansions of said rod and tube, whereby said diaphragm is flexed to its alternative positions.

In testimony whereof, I have signed my
15 name to this specification this 12th day of
June, 1930.

JOHN A. SPENCER.
